RECIPROCATING PUMP AND COMPRESSOR

Arthur Albert Connor, Hove, England

Application May 24, 1950, Serial No. 163,813
In Great Britain May 25, 1948

2 Claims. (Cl. 230—177)

1

This invention relates to reciprocating pumps and compressors for the delivery, pressurising or suction of liquids or gases, of the kind comprising a rotatable cylinder block having a plurality of radial cylinder bores each housing a piston which is reciprocated therein by slidably engaging a guide member disposed eccentrically to the axis of rotation of the block and rotated by the frictional engagement of the pistons.

The object of the present invention is to provide a simplified construction of such a pump.

According to the present invention, the pump comprises a cylindrical casing, one end of which is detachable and carries a fixed valve shaft on which the cylinder block rotates, and the other end of which carries a fixed stub shaft, eccentrically disposed with respect to the said valve shaft, and on which a cup-shaped guide is rotatably carried, said stub-shaft also serving as a bearing for a driving shaft coupled to the cylinder block.

The pistons engage with the guide member or the like on the inner periphery thereof by centrifugal force when the pump is running.

The valve shaft has axial passages which communicate at their inner end with the cylinder bores, the cylinder block and valve shaft together forming a rotary valve.

In a simple embodiment of the invention, the shaft comprises two bores passing inwardly from its external end parallel with each other and with the axis of the shaft and communicating each with a slot cut in the periphery of the end of the valve shaft inside the casing, the two slots being diametrically opposed.

The external ends of the two holes in the shaft form the inlet and outlet ports of the pump, and the slots in the shaft coat with passages in the cylinder block leading to the bores therein.

The guide member is a cup shaped annulus, having its internal diameter greater than the outside diameter of the cylinder block, and rotatable on the stub shaft fast to the end of the casing. The internal circumference of the cup-shaped guide member encloses the pistons in the cylinder block and serves to retain them therein. The stub shaft on which the cup shaped member is mounted is pierced by an eccentric axial hole through which hole passes the driving shaft.

The slots in the valve shaft are so arranged as to allow fluid to be drawn through one part thereof and into the bores of the cylinder block by the outward displacement of the corresponding piston during the first half of a cycle, and

2

cause the said fluid to be forced out through the other port as the piston is urged inwardly by coaction with the guide member during the second half of the cycle.

5 The valve shaft carrying the cylinder block may be provided with a suitable lubrication channel or channels to permit the flow of oil to the bearing surface between the cylinder block and the said shaft. As one of the valve slots cut 10 in the said shaft is for the intake side of the pump the pressure at or near said slot is reduced. Furthermore, if the casing, in which the cylinder block revolves, is sealed or substantially sealed, there will be a pressure built up inside 15 it due to leakage past the pistons. When the cylinder block revolves at high speed, any oil present is flung to the periphery of the casing inside and a suitable outlet can be provided to tap off some of this oil at this point. If a connection is made between the tapping point and the above mentioned lubrication channel where 20 provided, the difference in pressures is considerable and can provide an adequate flow of oil from the casing to the cylinder block bearing, thereby 25 greatly increasing the efficiency of the pump and providing an automatic lubrication and cooling means for the bearing.

The rotation of the guide member permits a very small relative rotation between the pistons 30 and the said guide member, whereby frictional losses are greatly reduced, and the pump is very quiet in operation.

In order that the invention may be more fully understood, a construction thereof is shown by 35 way of example in the accompanying drawings, wherein:

Fig. 1 shows a central vertical section through a pump.

Fig. 2 shows a section taken on the line I—I of 40 Fig. 1.

Fig. 3 shows a front elevation with one end of the casing and the cylinder block removed, looking into the casing.

Fig. 4 shows an elevation of the removable end 45 of the casing and the cylinder block.

Fig. 5 shows a central horizontal section through part of the end of the casing and valve shaft.

Fig. 6 shows a side elevation of the cylinder 50 block with one of the pistons thereof removed to show valve passages.

Fig. 7 shows a typical piston.

Fig. 8 shows a central vertical section through 55 a modification of the pump.

Fig. 9 shows a plan view of a detail of the modification of Fig. 8.

Fig. 10 shows a plan view of another detail of the modification of Fig. 8.

Fig. 11 shows an elevation of yet another detail of the modification of Fig. 8.

In these figures, 1 represents a casing having a removable end 2 and support legs 3. A stub-shaft 4 is rigidly attached centrally on the inside of the end wall of the casing 1 by means of screws 5 (only one of which can be seen in Fig. 1). 6 is a cup-shaped annular guide which is rotatably carried on the stub shaft 4. A driving shaft 7 passes rotatably through a bore in the stub shaft 4 offset from its axis and has on its inner end an inner coupling member 8 which also serves to retain the guide 6 on its shaft. The inner coupling member 8 coacts with an intermediate coupling member 9 loosely engaged therewith, which latter in turn coacts by means of tenons 10 with slots 11 provided in a flange 12 on a cylinder block 13, in such a manner that rotation of the driving shaft 7 causes rotation of the cylinder block 13. The block 13 is rotatably mounted on a valve shaft 14 which is rigidly set in the removable end 2 of the casing. At the centre of the cylinder block 13 is arranged a Phosphor bronze or like bearing ring 13*. 15 represents four equally spaced radial cylinder bores each receiving a solid piston 16 and having at their inner end two valve passages 17 spaced axially of the cylinder block. These are arranged to coact with valve slots 18 in such a manner as to form a rotary valve when the cylinder block 13 is rotated with respect to the valve shaft 14. Each valve slot leads by means of an axial bore 19 to the outer surface of the end 2 of the casing. One such bore 19 for the output of the pump (the lower one in Fig. 5) has a widened portion 20 at its outer end to receive a screw threaded union 21 (shown only in Fig. 5) which is also adapted to retain in position a cover plate 22 (in Fig. 5) serving to compress a felt or like washer 23 (in Fig. 5) against the end 2 of the casing in such a manner as to form a filter for the upper bore 19 in Fig. 5. Said filter also serves as a silencer for the air intake. The pistons 16 have peripheral grooves 24 which assist in retaining lubricant in the bores and serve to provide a more effective seal between the bores and the pistons. The ends of the pistons 16 are rounded as at 25 to enable them to coact with the inside periphery of the guide 6 with a minimum of friction in all their relative positions. 26 is an oil filler plug which can be screw-threaded into a filler aperture at the upper part of the body of the casing and which can carry a dipstick (not shown) for ascertaining the level of the lubricating oil.

Figs 8 and 9 show a modification in which lubrication of the valve shaft is improved by the provision of a forced oil feed. In this figure, a casing for the pump has two parts 27 and 28, part 27 carrying a valve shaft 29 on which is rotatably mounted a cylinder block 30 having pistons 31 in cylinder bores 32. Part 28 carries a stub shaft 33 on which is rotatably mounted a cup-shaped guide 34 coacting with the pistons 31. 35 is a driving shaft which is coupled to the cylinder block 30 by a coupling member 36. A disc 37 rotatively coupled to the end of the driving shaft 35 has a plurality of cups or depressed portions 38 and serves as an oil impeller. 39 is an oil feed channel in the part 27, and 40 is another oil feed channel forming a continua-

tion thereof in the valve shaft 29. 41 are oil outlets in the valve shaft for passage of oil to the bearing surface between the valve shaft and the cylinder block. The air pumped by the device emerges through the union 42 and passes through a pipe 43 and a union 44 to a hollow handle 45 which at its lower end has a stop-cock 46 controlling the flow through a bore 47 leading to a spring loaded relief valve 48 controlling the flow to a bore 49 which leads back into the interior of the casing through the end wall of part 27.

The operation is as follows:

When the pump is working, and a quantity of oil has been previously introduced generally into the casing, some of the oil at the lower part of the casing is caught by the rotating parts and by the impeller and is flung radially outwards. Some of it passes into the open upper end of the oil channel 39 and passes down the said channel to the channel 40 in the valve shaft. For the purpose of ensuring that oil will pass more readily into the channel 39, and to prevent it from escaping out of the peripheral openings of the casing, baffles may be included on the parts 27 and 28 of the casing. The oil received by the channel 40 is distributed through the outlets 41 to the adjacent bearing surfaces. Any oil which gets fed out with the compressed air passes through the pipe 43 to the handle 45 and runs downwardly therein to the stop-cock 46 and from there can flow back through the adjustable spring-loaded relief valve 48 to the bore 49, and is thereby returned to the inside of the casing. The path of the lubrication oil is indicated by the arrows.

Fig. 10 is a plan view of part 28 of the casing and shows (in broken line) a baffle 50 arranged on the inside upper wall of the casing near a filling hole 51 to prevent oil escaping through said filling hole.

Fig. 11 is an elevation of part 28 of the casing seen from the outside of the pump to show the baffle 50.

I claim:

1. A pump comprising a casing having a cylindrical portion and two ends one of which is detachable, a valve shaft fixedly mounted on said detachable end and having an outlet union, a hollow handle mounted on the casing and in communication with the outlet union, a stop-cock in the hollow handle, and a relief valve in the casing connected by bores to the stop-cock and the inside of the casing, whereby oil carried out through the outlet union is collected in the hollow handle and returned through the stop-cock and relief valve to the inside of the casing, a rotary cylinder block rotatably carried on the said valve shaft and forming a rotary valve therewith, a plurality of radial cylinder bores in the cylinder block, a piston in each said bore, a stub-shaft fixedly mounted on the other end for the casing eccentrically with respect to the said valve shaft, a cup-shaped guide rotatably carried by said stub shaft and driven by slidably engagement with the outer ends of the pistons, a driving shaft for the cylinder block carried in an eccentric bore in the said stub-shaft, and coupling means between said driving shaft and the cylinder block, whereby when the cylinder block is rotated by the driving shaft the pistons in said block are urged outwardly by centrifugal force to slidably engage the cup-shaped guide and are thereby reciprocated in the cylinder bore.

2. A pump comprising a casing having a cy-

cylindrical portion and two ends one of which is detachable, a valve shaft fixedly mounted on said detachable end and having an outlet union, a hollow handle mounted on the casing and in communication with the outlet union, a stop-cock in the hollow handle, and a relief valve in the casing connected by bores to the stop-cock and the inside of the casing, whereby oil carried out through the outlet union is collected in the hollow handle and returned through the stop-cock and relief valve to the inside of the casing, axial passages and axially-separated slots in the valve shaft, a rotary cylinder block rotatably carried on the valve shaft, valve passages in the cylinder block whereby the cylinder block forms a rotary valve with the valve shaft, a plurality of radial cylinder bores in the cylinder block, a piston in each said bore, a stub-shaft fixedly mounted on the other end for the casing eccentrically with respect to the valve shaft, a cup-shaped guide rotatably carried by said stub-shaft and driven by slidable engagement with the outer ends of the pistons, a driving shaft for the cylinder block carried in an

eccentric bore in the stub-shaft, a loose coupling member for the driving shaft and the cylinder block, a slotted circular flange on the cylinder block, and tenons on the coupling member to engage in the slots of the flange, the pistons in the cylinder block being urged outwardly by centrifugal force when the cylinder block is rotated and being reciprocated by slidable engagement with the cup-shaped guide.
